UNITED STATES PATENT OFFICE

117,668

DESIGN FOR A DOLL

Elizabeth A. Huestis, Greenville, R. I.

Application August 29, 1939, Serial No. 86,923

Term of patent 7 years

To all whom it may concern:

Be it known that I, Elizabeth A. Huestis, a citizen of the United States of America, residing at Greenville, county of Providence, State of Rhode Island, have invented a new, original, and ornamental Design for a Doll, of which the following is a specification, reference being had to the accompanying drawing, forming a part thereof.

Fig. 1 is a front elevational view of a doll embodying my design;

Fig. 2 is a side elevation of the doll as viewed from the right of Fig. 1; and

Fig. 3 is a back view of the doll.

I claim:

The ornamental design for a doll, substantially as shown.

ELIZABETH A. HUESTIS.
